To all whom it may concern:

Be it known that I, JOHN B. Figure 1 is a side elevation of a closet bowl, showing my new design,

Figure 2 is a top plan view of the same,

Figure 3 is a bottom plan view of the bowl,

Figure 4 is a front elevation of the bowl,
and

Figure 5 is a rear elevation of the bowl. The distinguishing features of the design are the flattened base plate having its upper marginal edge beveled and the stand for supporting the bowl arranged on the base plate with its flat side faces and flat inwardly inclined front and rear faces with the beveled corners and the outwardly bulged portion on the stand above the inclined front face.

I claim:

The ornamental design for a closet bowl as shown and described.
